[57] ABSTRACT

This invention relates to a fixation lamp assembly for an ophthalmological instrument, having a head rest for a patient, a light collimator, and bearing means disposed between the head rest and the collimator allowing adjustment of the collimator relative to the head rest about at least two axes intercepting the optical axis of the collimator in the center of rotation of an eye of the patient. Thus the patient is able to recognize the fixation mark of the collimator in any position within his field of vision with ease and uniform quality, without turning his head.

FIG. 6

OPHTHALMOLOGICAL FIXATION LAMP ASSEMBLY

This invention concerns an ophthalmological fixation-lamp assembly movable about at least two different axes while maintaining proper focal alignment relative to the eye of a patient. A fixation lamp is typically used to fix the direction of sight of the eye of a patient so as to facilitate ophthalmological examination. The patient should be able to recognize a fixation-mark, photograph, or other indicia of the fixation lamp throughout his field of vision with ease and similar quality, without turning the head. This is obtained according to the present invention in that a collimator is hinged around two axes which intersect the collimator optical axis in the center of motion of the eye.

The invention will be explained in detail by referring to the attached drawings, which show an example of a preferred embodiment.

BRIEF DESCRIPTION OF THE DRAWINGS

FIG. 1 is a side elevational view of a fixation lamp assembly according to the present invention;

FIG. 2 is a partial top plan view with parts broken away of the guide of the fixation lamp assembly looking in the direction of the arrow II in FIG. 1;

FIGS. 3 and 4 are partial sectional views of details of the assembly of FIG. 1;

FIG. 5 is a partial sectional view taken along line V—V in FIG. 4; and

FIG. 6 is a partial view taken along line VI—VI in FIG. 2.

DESCRIPTION OF THE INVENTION

The shown fixation-lamp is attached to a holder, from which two lateral supports 1 and 2 are shown. These supports are fixed on a table or the like, which is not represented, and on which an instrument, for instance a slitlamp, may also be attached for examining an eye of the patient. The patient can put his forehead against a ribbon or head support band 3, which is connected with the supports 1 and 2. By using the head support 3, the position of the eyes, from which one (4) is schematically drawn in FIG. 1, may be approximately determinated relative to the holder and its supported fixation lamp.

The holder has a yoke 5 which extends between the ends of the supports and in which a carriage 13 can be moved along a straight guide. To this carriage is fixed an extension arm 6 having parts 6a and 6b which are connected by a vertical-axial joint 7. At the lower end of support part 6b a bent, substantially L-shaped collimator 8 is hingedly mounted on bearings, and contains a lamp 41 and a fixation-mark, whose image can be viewed through a lens 9 and a mirror 10. As FIG. 1 shows, the axis A of the joint 7 axis B, of the bearing of the collimator 8, and axis C of the lens 9 intersect at the center of rotation of the eye 11.

FIGS. 2, 4 and 6 show the construction of the straight guide for the fixation lamp. Between the side flanges of yoke 5 is fixed a guide bar 12, on which the carriage 13 is exactly guided along axial bearings. The carriage is secured against swinging around guide bar 12 by bearings 15 which run in a groove 14 of yoke 5. The bearings 15 are eccentrically fixed on pivots 16 (FIG. 6) which are disposed in holes and are secured against rotation by screws 17. When the screws are loosened, the pivots 16 can be rotated until the bearings 15 rest

against the walls of the grooves to guide the carriage without play in the desired position. Then the screws can be fastened. The carriage is provided with adjustable stops 18, which determine the limits of travel.

5 At the rear panel of yoke 5 is fixed a stop rail 19 with two stop recesses or detents 20. At the carriage is located an index roller 21, which cooperates with the stop recesses and determines either of two positions of the carriage in front of the respective eyes of the patient. The inclined edge-surfaces 19a of the stop rail 19 are explained below.

At the rear panel of yoke 5 is also fixed an insulated rail 22, which is connected with a conductor 25 which passes through the support 1. A spring-loaded, insulated brush 24, which is located in the support part 6a pushes at one end against the rail 22 and is connected at the other end by a biasing spring to a conductor 25, which is located in the arm support 6.

The joint 7 of arm 6 (FIGS. 4 and 5) has a plate 26 20 which is connected with support part 6a and a plate 27, which is connected to support part 6b. On the hub 28 of plate 26 is pivoted a disk 29, which is connected to plate 27 and presses against a friction liner 31 under the action of star-spring 30 which is also mounted on hub 28. Thus parts 6a and 6b are hingedly connected, but the turning movement can only be transmitted by overcoming a certain amount of friction.

The collimator 8 (FIG. 3) is attached over a tube 32 and secured with a bolt 33 and nut 34 which a slot in the end of the collimator. The tube 32 is pivoted in a bore of the lower, enlarged end of part 6b. It has a groove 35 accommodating a springloaded ball 36. This ball causes a certain friction in the pivot bearing of tube 32 and, because of the small distance to the pivot 46, 35 prevents axial displacement. The conductor 25 is guided over a terminal and a springloaded brush 37 to a sliring 38 which is fastened in an insulated manner on tube 32. The sliring has an external insulation layer 39 which serves as an operating handle for the turning of tube 32 and collimator 8. The sliring is connected by a threaded member, which is disposed in the hollow operating handle, to an insulated spring-loaded contact 40, which is inside tube 32. This contact 40 is connected over a common spring to a spring-loaded contact 42 which presses against the central pin of lamp 41.

In the collimator 8 is a tube 43 which can be adjusted with knob 44 in an axial direction and which remains in the adjusted position by friction. In the front end of tube 43 is disposed on opaline body 45 having a fixation mark. The zero position of tube 43 is chosen such that the fixation mark is in the focal point of lens 9. A normal-sighted patient sees the image of the fixation mark at infinity. For near or far sighted patients the fixation mark can be adjusted by the handle with the aid of a scale (not shown) on collimator 8, so that the mark appears in focus.

In operation, the patient places his forehead against band 3 and his chin on an optional chin support (not shown). The carriage 13 is then moved to a detent-determined position in which it is approximately aligned over the patient's eye which is not to be examined. When the illumination is on, the current for the lamp 41 flows over conductor 23, rail 22, brush 24, conductor 25, brush 37, sliring 38, contacts 40 and 42, and lamp 41 to ground. The examiner can then fully control eye position for substantially the entire range of

eye movement provided axis A of joint 7 and axis B of the collimator go through the center of rotation 11 of the eye. An eventual correction can be made through a slight lateral displacement of the head of the patient, for example, by varying the height of the chin rest. As the two cited rotation-axes go through point 11 of the eye, the fixation mark is visible to the patient at all positions of joint 7, as well as collimator 8, if lens 9 is in his field of vision. This condition is fulfilled at a minimum angle of 45° between the horizontal rotation axis B and the optical axis C. The eye to be examined follows the movements of the eye which looks at the fixation mark and stays in the fixed direction during examination. For the examination of the other eye the carriage is displaced by the mean eyes-distance to the other stop-position. The adjustment is the same as described above.

When the fixation lamp is not used, the carriage is moved over the stop-position on one side, to an endposition, which is determinated by the stops 18, whereupon the index roller 21 comes to rest on one of the inclined edge-surfaces 19a of stop rail 19 and thus secures the carriage. With fine adjustment of the stops it is possible to determine exactly the end positions.

It is possible to change details of the above described fixation lamp relative to the shown embodiment. Thus, support part 6a may not be fastened to a carriage which can be moved along yoke 5, but can be hinged directly to the yoke with a joint similar to joint 7. This joint has preferably means for stops, which determines two rotational positions of part 6a, so that axis A of joint 7 goes through one of both eyes of the patient for each of those turning positions. If necessary, part 6a can be made to swing past the stop position of the joint in two positions of rest, if the fixation lamp is not used. The resistance in the stop positions of part 6a must be such, that part 6b can be turned around without turning part 6a out of its stop position.

What is claimed is:

1. An ophthalmological fixation lamp assembly, comprising a head-rest for a patient; a light collimator having an optical axis; bearing means coupling said collimator to said head-rest for movement of said collimator about a plurality of axes intercepting one another at a position corresponding to the center of rotation of an eye of the patient, said bearing means constraining the optical axis of said collimator to pass through said position of interception independently of the position of said collimator about said plurality of axes whereby said eye may be fixed at any position while the other

eye of the patient is examined; said bearing means including guide means disposed over said head-rest for enabling horizontal movement of said collimator relative to said head-rest for bringing the collimator in front of either eye of the patient; said guide means having a guide element fixedly attached over said head rest, and carriage means movable along said guide element; and said bearing means having a first arm extending from said carriage means, and a second arm pivotally connected with said first arm for rotation about one of said plurality of axes; said collimator being pivotally coupled to said second arm for rotation about another of said plurality of axes.

2. The fixation lamp assembly according to claim 1 wherein said second arm is provided with an insulated brush connected to a source of operating potential, and said collimator is provided with an annular electrical contact cooperating with said brush to provide said potential to said collimator.

3. The fixation lamp assembly according to claim 1 wherein said collimator extends from one side of said second arm and includes a knob extending from the opposite side of said second arm to facilitate rotational positioning of said collimator and said plurality of axes.

4. The fixation lamp assembly according to claim 1 wherein said guide means further comprises means cooperating with said carriage means to determine the horizontal position of said collimator in front of the eyes of the patient.

5. The fixation lamp assembly according to claim 1 wherein one of said plurality of axes is horizontal and another is vertical.

6. The fixation lamp assembly according to claim 1 wherein said collimator has fixation indicia and means for moving said indicia in both directions out of the focal point of the collimator lens.

7. The fixation lamp assembly according to claim 1, wherein said guide element is provided with an insulated rail, electrically connected to a source of operating potential, said rail being in contact with a brush, which is electrically connected to said collimator.

8. The fixation lamp assembly according to claim 1 wherein said guide means includes stop means cooperating with said carriage means to determine rest and end positions of said carriage means outside an operation range.

9. The fixation lamp assembly according to claim 1 wherein said optical axis of said collimator is obliquely disposed relative to said plurality of axes.
